ABSORPTION TYPE REFRIGERATING SYSTEM

Eric H. Ryden, Bedford, and Albert C. Schickler, Beechwood, Ohio, assignors to The Bryant Heater Company, Cleveland, Ohio, a corporation of Ohio

Application August 12, 1938, Serial No. 224,453

9 Claims. (Cl. 62—118)

This invention relates to intermittent absorption type refrigerating systems, its object being to provide improved means for producing at the proper times a cooling effect upon either or both of the boiler-absorber and receiver or condenser.

More particularly the invention has for its object to provide a secondary cooling system, independent of fluid connection with the primary refrigerating system, and so arranged as to be capable of receiving heat by transfer from the primary refrigerating system and to conduct the heat away for dissipation elsewhere.

A further object is to provide a secondary cooling system of the kind described, charged with its own refrigerant separate and apart from the refrigerant in the primary system, and consisting of a closed circuit embodying a condenser at which the absorbed heat is dissipated, as well as an evaporator portion in heat transfer relation with a part of the primary refrigerating system, such as the boiler-absorber or the receiver or condenser, for the purpose of utilizing the effect of the secondary cooling system for the purpose of applying a cooling effect to the primary refrigerating system.

Further objects of the invention are in part obvious and in part will appear more in detail hereinafter.

In the drawings Fig. 1 represents, diagrammatically, one form of apparatus embodying the invention, the cooling effect being applied to the boiler-absorber alone; and Fig. 2 is a similar diagrammatic view of another system embodying the invention in which the cooling effect is applied both to the boiler-absorber and to the receiver or condenser.

While the invention may be applied for use with any form or arrangement of intermittent or cyclic absorption type refrigerating system, the drawings, for simplicity of illustration and in no sense of limitation, illustrate an absorption type refrigerating system comprising the usual boiler-absorber 1 communicating by way of the pipe 2, liquid seal trap 3, rectifier 4 and pipe 5 with the evaporator 6, which in turn communicates by pipe 7 with the condenser and receiver 8. The cooling coils 9 of the evaporator communicate by way of a pipe 10 with a liquid seal trap 11 within the evaporator, said trap communicating by drain pipe 12 with the trap 3, the latter communicating by return pipe 13 with the boiler-absorber.

The primary refrigerating system described operates in the usual manner. Heat applied by burner 14 to the boiler-absorber 1 distills the

refrigerant, such as ammonia, from the absorbing liquid, such as water, and drives it by way of pipe 2 and trap 3 to the rectifier 4 from which entrained absorbing liquid returns to the boiler.

5 The vapor continues by way of pipe 5 to the evaporator and by pipe 7 to the condenser-receiver where the liquefied refrigerant collects pending completion of the heating phase of the cycle.

10 Upon reversal, when burner 14 is turned off and the supply of heat ceases, the boiler-absorber cools down, resulting first in return of the liquefied refrigerant from the condenser-receiver by way of pipe 7 to the evaporator, followed by evaporation of the liquid in the evaporator and return of the vapor to the boiler by way of pipe 13 for absorption in the absorbing liquid.

15 Drain pipe 10, trap 11 and drain return pipe 12 operate intermittently, once during each complete cycle, to return to the boiler any excess liquor remaining in the evaporator.

20 The draining effect is accomplished as follows: At the end of each refrigerating period a quantity of liquid rich in absorbent remains 25 in the bottom of the evaporating coils 9 and the pipe 9a by which they communicate with the evaporator 6. When, at the beginning of the next refrigerating period, the condensate coming from the condenser 8 is discharged into the 30 evaporator 6 it forces the liquid in the coils 9 and pipe 9a up through pipe 10 into the trap vessel 11 within the evaporator reservoir 6. This is merely a matter of displacement of liquid. As the level of liquid rises in evaporator 6 it 35 also rises in the pipe 10, which finally overflows into the vessel 11. At the end of this refrigerating period the concentration of refrigerant in the liquid in vessel 11 is very low. Said vessel communicates with the seal 3 by pipe 12, whose 40 upper end is disposed inside of and near the bottom of vessel 11 and whose lower end is disposed below the liquid level in the seal 3. During the ensuing heating period the rising pressure in the refrigerating system compresses the 45 vapor in conduit 12 between its two sealed ends. The liquid therefore rises into the pipe 12 both from the trap 3 and the receiver 11, finally spilling over from the receiver 11 past the bend at the top of the pipe 12, and starting a siphoning effect at the upper end of the drain tube, causing the liquid to rise from vessel 11 and flow by way of pipe 12 back to seal 3 and thence to the boiler-absorber.

50 The secondary cooling system forming the subject matter of the present invention may be

applied to one or more of the parts of the primary refrigerating system which it is desired to cool, such as either the boiler-absorber or the condenser and receiver, or both thereof. In Fig. 1 the secondary cooling system is applied for its effect alone upon the boiler-absorber. Referring to the arrangement shown in Fig. 1, the secondary cooling system includes an evaporator part suitably designed for transfer of heat to it from the boiler-absorber, such as a pipe 17 lying in the liquid space of the boiler-absorber below its normal liquid level A—A. The evaporator part may also include a pipe 15 in the vapor space in the boiler absorber above its normal liquid level A—A and, if desired, provided with heat transfer fins 16 in the vapor space for increasing the heat transfer effect. Said two pipes 15, 17, together forming the evaporator portion, communicate together or in parallel, with a riser pipe 18 communicating with a liquid seal trap 19 beyond which a pipe 20 extends upwardly to the top of a condenser 21 which includes coils or turns of pipe provided with heat radiating fins or members 22 if desired. The condenser drains to a descending pipe 23 communicating with the liquid seal trap 24 which, in turn, communicates with a descending pipe 25 having a downward bend 26 at the boiler-absorber communicating in parallel or with each of the pipes 15, 17. The condenser 21 need not be directly above the boiler-absorber, as shown, but spatially is independent thereof. Also, the boiler-absorber 1 and the parts associated therewith may be heat-insulated from the remaining portions of the apparatus as by an insulating shield 27. Also, the burner 14 preferably is provided with one or more jets 14a beneath, and arranged to supply heat to, the pipe bend 26.

The secondary cooling system is independent of liquid communication with the primary refrigerating system. In other words, each is charged with its own refrigerant. The two refrigerants may be the same but, preferably, the refrigerant in the secondary cooling system should have a low vapor pressure at high temperatures. For example, when using ammonia in the primary refrigerating system, the refrigerant in the secondary cooling system may be methylene chloride (commonly known as carrene) or sulfur dioxide. Other refrigerants may be used, however.

In operation, during the heating period, heat will be applied by burner 14 to the boiler-absorber and by the flame jets 14a thereof to the U-bend 26. In the primary refrigerating system the heating phase of the cycle goes on as usual. In the secondary cooling system, the effect of the heat applied to the U-bend 26 is to vaporize some of the liquid in said bend. The vapor produced in the leg of the U-bend communicating with pipe 25 forces the liquid out of this pipe through the trap 24 into the lower part of condenser 21 and in the other leg of the U-bend forces the liquid out of the evaporator tubes 15, 17 upwardly through pipe 18 and trap 19, establishing counterbalancing liquid columns, one in pipe 23 and the lower part of condenser 21 and the other in pipe 25 above the liquid seal trap 19. When this condition is reached there will be no material circulation or flow in the secondary cooling system, but the liquid refrigerant remains trapped in condenser 21 at a pressure only slightly higher than that corresponding to the temperature of air around the condenser 21.

When the burner 14 is turned off and the supply of heat ceases, liquid begins to flow downwardly to the bottom of the secondary cooling system, producing a greater liquid column in pipe 23, trap 24 and pipe 25 than the liquid column in pipe 20. As the liquid from pipe 25 finally enters the evaporating portion 15, 17 of the secondary cooling system, pressure is built up therein, blowing over the liquid seal in the rising leg 20, toward the condenser. Circulation starts and continues, the liquid refrigerant evaporating in the evaporator tubes 15, 17, the vapors rising through leg 18, 19, 20 to be liquefied in condenser 21 and returned for reuse.

The condenser 21 obviously is located at some place where its heat will be dissipated elsewhere than to the primary refrigerating system, such as to the atmosphere by a current of air flowing across the turns or coils of the condenser.

Due to the fact that the cooling effect of the secondary cooling system starts as soon as the heat is turned off, regardless of any change in the primary system, it is possible to heat insulate the generator-absorber from the rest of the apparatus. The production of a cooling effect at the generator-absorber induces the return of the condensate to the evaporator of the primary system and the subsequent production of refrigeration therein.

The secondary system being inactive during the heating period, it is possible to lower the concentration of the absorption liquid. No "absorption loop" communicating with the absorber is required, so that it is unnecessary to store strong solution in this part of the system and the charge of refrigerant ordinarily required for the absorption loop may be dispensed with.

Fig. 2 illustrates another embodiment of the invention in which a cooling effect is produced by the secondary cooling system at both the boiler-absorber and the receiver or condenser.

Here, too, the primary refrigerating system may be of any suitable form and for convenience is illustrated as of substantially the same form as that shown in Fig. 1, consisting of a boiler-absorber 30 communicating by pipe 31 with the liquid seal trap 32 from which, during the heating operation, vapor flows by way of pipe 33 and rectifier 34 to the evaporator 35 and to condenser-receiver 36, from which the liquefied refrigerant is returned to the evaporator 35. During the refrigerating phase of the cycle the vapors return by way of pipe 33 to the trap 32 and thence by way of pipe 37 to the boiler-absorber beneath the level of liquid therein. 38 indicates the drain return pipe, operating as before described.

Condenser receiver 36 is shown equipped at its right-hand end with a standard form of valve, communicating with a pipe extending along the upper portion of the space within said condenser receiver, said valve being used both for charging the system with refrigerant and for purging it of inert gas.

The secondary cooling system, in this form of the invention, includes a suitable evaporator portion at the boiler, shown as a double-walled hollow cylinder 39 forming a chamber 40 which communicates by a riser pipe 41 with a liquid seal trap 42, communicating by an upward bend in the pipe 43 with a liquid seal trap or vessel 44. The rising leg also includes a pipe 45 leading from the trap 42 to the top of the condenser 46 which drains to a reservoir 47 communicating by way of a trap 48 and pipe 49 with chamber

ber 48. Condenser-receiver 36 is jacketed, as at 50, to provide a second evaporator portion for the secondary cooling system, the chamber 51 in the jacket communicating by a rising pipe 52 with the top of the condenser 46, and also communicating by the pipe 53, with the reservoir 47.

The boiler-absorber 30 may be heat insulated from the rest of the apparatus, as by the insulating shield 54, and the vessel 44 may be disposed, as by the wall 55, in a separate flue duct from the main duct in the shield 54. Here, also, the burner 56 for heating the boiler-absorber may have one or more jets 56a located to heat vessel 44.

The operation of the primary refrigerating system shown in Fig. 2 is the same as that shown in Fig. 1, including both the heating and refrigerating phases of the cycle, as well as the drain effect. Description thereof, therefore, need not be repeated.

It will be assumed that in the system shown in Fig. 2 the same refrigerants may be used for both the primary and secondary systems, as in the form shown in Fig. 1. The secondary cooling system, in Fig. 2, is charged with sufficient refrigerant to insure a liquid level in the reservoir 47 with the jacket chamber 51 and the several liquid seals completely filled, while the reservoir 47 should also have sufficient additional capacity to take up or receive all of the liquid refrigerant from chamber 51 when its liquid volume is displaced during one part of the operating cycle of the machine.

So far as the operation of the secondary cooling system is concerned, when burner 56 is lighted, heat is applied not only to the boiler-absorber but also to the vessel 44, the liquid in which is forced by the pressure generated therein upwardly through pipe 43 into trap 42, to fill the same and establish a liquid seal in pipe 45 leading to the top of the condenser 46. The volume of vessel 47 is sufficiently large to insure a liquid seal height B at the trap 42 greater than the liquid seal height C that is formed at the same time at the trap 48, as the liquid in the chamber 40 is forced out of this vessel into reservoir 47 by the heat supplied to chamber 44 from the heated absorption solution in the generator-absorber 30. Thus, in a short time, chamber 40 contains only superheated vapor and practically no heat transfer takes place between the generator-absorber and the secondary cooling system. Any liquid that may come back through pipes 41 and 49 from the traps 42 and 48 respectively to chamber 40, is immediately re-evaporated and returned to said traps. The heating cycle, therefore, progresses without effect one way or the other at the boiler-absorber.

As the heating cycle continues, warm vapor of the primary refrigerant gradually finds its way to the condenser-receiver 36, causing evaporation of the secondary refrigerant in chamber 51. The vapor produced in the secondary cooling system rises through pipe 52, is condensed in the condenser 46, flows by gravity to vessel 47 and returns by pipe 53 to chamber 51 to be re-evaporated for accepting more heat from the condenser-receiving and carrying it away to the condenser 46 for dissipation there. During this phase of the cycle, therefore, a cooling effect is being produced at the condenser-receiver 36 by the conjoint operation of the evaporating chamber 51 and condenser 46, but no cooling effect is being produced at the boiler-absorber.

When the burner 56 is shut off, the vessel 44 is

cooled and the pressure therein lowers. The liquid in trap 42 and pipe 45 then returns to vessel 44, clearing the way in the rising leg 41, 42, 45, for flow of vapor from the cooling cylinder or evaporating chamber 40 within the generator-absorber, to the condenser 46, liquid refrigerant in the secondary cooling system coming in to chamber 40 by way of pipe 49 from the vessel 47, as the result of the liquid head therein. Thus, circulation of secondary refrigerant is established from the evaporating chamber 40 by way of rising leg 41, 42, 45, to condenser 46, and by way of reservoir 47, trap 48 and pipe 49 back again to the evaporating chamber 40, with the net effect of cooling the boiler-absorber by transfer of heat to the secondary cooling system for dissipation at the condenser 46.

As the temperature of the generator-absorber, during this portion of the cycle, is considerably higher than that of condenser 36 and its cooling jacket chamber 51, the chamber 51 becomes filled with secondary liquid refrigerant, which remains here, inactive, for the duration of the absorption or refrigerating period of the primary refrigerating system.

This arrangement, therefore, without valves or other mechanically operating parts, alternately effects the cooling of both the condenser and the generator-absorber of an intermittently operating absorption type refrigerating system, using a single heat dissipating element, the condenser 46, to perform both functions.

With this arrangement it is possible to utilize a secondary cooling system charged with a refrigerant which permits the use of copper in the finned coil, and to use one finned coil for cooling both the condenser and the generator-absorber, thus materially increasing efficiency of the apparatus. Also, the use in the secondary cooling system of a refrigerant having a lower vapor pressure than the refrigerant in the primary refrigerating system, makes it possible to reduce the maximum pressure in the secondary cooling system, as will be readily understood. Other advantages will be apparent to those skilled in the art.

What we claim is:

1. The combination with a primary refrigerating system of the intermittent absorption type including generator-absorber and condenser elements in circulatory communication with each other, of a secondary cooling system including a condenser member and two evaporator members both in closed circulatory communication with said condenser member and independent of communication with the primary refrigerating system, one of said evaporator members being in heat transfer relation with the said generator-absorber element and the other with the said condenser element, and means whereby the generator-absorber-cooling evaporator member is effective during only the refrigerating phase of the cycle.

2. The combination with a primary refrigerating system of the intermittent absorption type including generator-absorber and condenser elements in circulatory communication with each other, of a secondary cooling system including a condenser member and two evaporator members both in closed circulatory communication with said condenser member and independent of communication with the primary refrigerating system, one of said evaporator members being in heat transfer relation with the said generator-absorber element and the other with the said condenser element, and means whereby the con-

denser-cooling evaporator member is effective during only the heating phase of the cycle.

3. The combination with a primary refrigerating system of the intermittent absorption type including generator-absorber and condenser members, of a secondary cooling system comprising condenser and evaporator members in sealed circulatory communication with each other and independent of communication with the primary refrigerating system, the said evaporator member being in heat transfer relation with one of the elements of the primary refrigerating system, and the said secondary cooling system including rising and descending legs between its evaporator and condenser members, one thereof having a liquid seal trap, and a receiving vessel communicating therewith.

4. The combination with a primary refrigerating system of the intermittent absorption type including generator-absorber and condenser members, of a secondary cooling system comprising condenser and evaporator members in sealed circulatory communication with each other and independent of communication with the primary refrigerating system, the said evaporator member being in heat transfer relation with one of the elements of the primary refrigerating system, and the said secondary cooling system including rising and descending legs between its evaporator and condenser members, the said rising leg being provided with a liquid seal trap and a receiving vessel communicating therewith.

5. The combination with a primary refrigerating system of the intermittent absorption type, including generator-absorber and condenser elements in circulatory communication with each other, of a secondary cooling system including a condenser member, two evaporator members, and a receiving vessel in circulatory communication such that the receiving vessel collects the condensate and supplies it to the said evaporator members, one of said evaporator members being in heat transfer relation with the said generator-absorber element and the other with the said condenser element.

6. The combination with a primary refrigerating system of the intermittent absorption type, including generator-absorber and condenser elements in circulatory communication with each other, of a secondary cooling system including a condenser member, two evaporator members, and a receiving vessel in circulatory communication such that the receiving vessel collects the condensate and supplies it to the said evaporator members, one of said evaporator members being

in heat transfer relation with the said generator-absorber element and the other with the said condenser element, and a second receiving vessel also forming part of said secondary cooling system and communicating with a conduit leading to the condenser thereof and adapted when heated to prevent circulation through that evaporator of the secondary system which is in heat transfer relation with the generator-absorber element.

7. The combination with an intermittent absorption type refrigerating system including generator-absorber and condenser elements, of a secondary cooling system including an evaporator member in heat transfer relation with one of said elements and a condenser member communicating therewith, the said evaporator and condenser members being charged with volatile refrigerant and in closed communication with each other independent of the refrigerating system, heating means for the generator-absorber, and means adapted when the heating means is turned on to evacuate the liquid from said evaporator member.

8. The combination with an intermittent absorption type refrigerating system including generator-absorber and condenser elements, of a secondary cooling system including an evaporator member in heat transfer relation with one of said elements and a condenser member communicating therewith, the said evaporator and condenser members being charged with volatile refrigerant and in closed communication with each other independent of the refrigerating system, heating means for the generator-absorber, and means adapted when the heating means is turned off to clear the gas passage in the secondary cooling system and induce circulation therein.

9. The combination with an intermittent absorption type refrigerating system including generator-absorber and condenser elements, of a secondary cooling system including an evaporator member in heat transfer relation with one of said elements and a condenser member communicating therewith, the said evaporator and condenser members being charged with volatile refrigerant and in closed communication with each other independent of the refrigerating system, heating means for the generator-absorber, and means adapted as the heating means is turned on or off respectively to evacuate the liquid from or supply liquid to the said evaporator member.
